United States Patent Office

Des. 204,921
Patented May 24, 1966

204,921

COMBINED HEATING AND MASSAGING UNIT

Samuel L. McNair, Overland Park, Kans., assignor to The Songrand Corporation, a corporation of Missouri

Filed Sept. 23, 1965, Ser. No. 87,149

Term of patent 14 years

(Cl. D83—1)

Fig. 1.

Fig. 2.

Fig. 3.

Fig. 4.

Fig. 5.

FIG. 1 is a top plan view of a combined heating and massaging unit embodying my new design;

FIG. 2 is a side elevational view of same; the other side being substantially the same as the side shown;

FIG. 3 is a bottom plan view of same;

FIG. 4 is an end elevational view taken from the left hand end of FIG. 2; and

FIG. 5 is an end elevational view taken from the right hand end of FIG. 2.

I claim:

The ornamental design for a combined heating and massaging unit, as shown and described.
